(57) **CLAIM**

The ornamental design for an astronaut electric toothbrush, as shown and described.

DESCRIPTION

FIG. 1 is a perspective view of an electric toothbrush showing our new design;

FIG. 2 is a top plan view thereof;

FIG. 3 is a first side plan view thereof;

FIG. 4 is a bottom plan view thereof;

FIG. 5 is a other side plan view thereof;

FIG. 6 is atop end view thereof;

FIG. 7 is a bottom end view thereof;

FIGS. 8-14 comprise a second embodiment of the subject electric toothbrush design.

FIG. 8 comprises a perspective view thereof;

FIG. 9 is a top plan view thereof;

FIG. 10 is a first side plan view thereof;

FIG. 11 is a bottom plan view thereof;

FIG. 12 is the other side plan view thereof;

FIG. 13 is a top end view hereof; and,

FIG. 14 is a bottom end view thereof.

The parts shown in broken lines in FIGS. 1-7 and 8-14 are shown for illustrative purposes only and form no part of the claimed design.
